UNITED STATES PATENT OFFICE.

MICHAEL KRECKOWSKI, OF NEW YORK, N. Y.

EXTENSION-TABLE.

1,167,905.

Specification of Letters Patent. Patented Jan. 11, 1916.

Application filed July 7, 1915. Serial No. 38,444.

To all whom it may concern:

Be it known that I, MICHAEL KRECKOWSKI, a subject of the Emperor of Austria-Hungary, residing at New York, in the county of New York and State of New York, have invented certain new and useful Improvements in Extension-Tables, of which the following is a specification.

This invention relates to new and useful improvements in extension tables.

The primary object of this invention is the provision of a table adapted for compact positioning when not in use but readily extending longitudinally of the center thereof in its operative table formation.

A further object is the provision of a table structure provided with a plurality of foldable leaves mounted thereon and with laterally positioned auxiliary foldable supports for the leaves arranged substantially inclosed when the table is in its closed position.

A still further object is to provide a table supporting a plurality of foldable leaves thereon and having leaf supports foldably positionable within the top thereof beneath the leaves and providing a compact arrangement of readily extending table members.

With these general objects in view and others that will appear as the nature of the invention is better understood, the same consists in the novel combination and arrangement of parts hereinafter fully described, illustrated in the accompanying drawings and then claimed.

In the drawings forming a part of this application and in which like designating characters refer to corresponding parts throughout the several views:—Figure 1 is a perspective view of the device with all of the leaves folded and with one of the leaf supports extended and the other partially folded. Fig. 2 is a side elevation of the device with the extension leaves and supports extended at one side of the table and in their folded relations at the other side thereof. Fig. 3 is a top plan view of Fig. 2. Fig. 4 is an enlarged vertical sectional view through a portion of the device taken adjacent one of the side rails positioned as shown in Fig. 1. Fig. 5 is a sectional detail view taken upon line V—V of Fig. 4, and Fig. 6 is a horizontal detail sectional view of a portion of the device partially folded.

Referring more in detail to the drawing,

a main table member or unit 10 is provided having a supporting top 11 and the usual legs 12 at the four corners thereof. Three panels or leaves 13 of identical size are hinged to each other by alternately arranged hinges 14 and to the opposite edges of the table 10 by hinges 15, the hinging being such as to allow the leaves at the opposite sides of the table to be folded together in two separate groups of equal size and substantially covering the said top 11 when positioned thereon as best illustrated in Fig. 1 of the drawing. Opposite supports of identical form are arranged for each set of three leaves and each support consists of a main frame 16 having side beams 17 longitudinally slidable within opposite slots 18 in the adjacent side wall 19 of the table 10. This frame 16 has a forwardly arranged transverse facing strip 20 adapted for flush reception between the opposite shoulders 21 formed by the tops of the table legs 12. The beams 17 are prevented from being completely removed from the slots 18 by means of depending flanges 22 upon their inner ends adapted to engage an edge 23 of the table side 19. Auxiliary legs 24 are forwardly hinged as at 25 to the lower surface of the beams 17 and are adapted to fold flatly thereagainst as shown in dotted lines in Fig. 4 and whereupon the beams 17 may be slid inwardly of the slots 18 while the legs 24 will slide within the lower extensions 26 of the said slots 18 and thus position the beams and legs 24 completely beneath the table top 11 and with the facing strip 20 lying flush with the front faces of the opposite table legs 12.

The beams 17 are provided with central longitudinal slots 27 upon their upper sides within which the opposite side bars 28 of an auxiliary supporting frame are slidably mounted and are prevented from removal by means of the downwardly extending inner ends 29 of the said bars which are adapted to engage the adjacent edge of the facing strip 20, it being noted that staples 30 are carried by the beams 17 overlying the bars 28 for preventing a separation of the bars from the said beams. A front strip 31 connects the bars 28 and is adapted to fill the upper cut away portion 32 of the facing strip 20 when the bars 28 are completely inclosed within the beam slots 27. Front legs 33 are hinged as at 34 to the under sides

of the bar 28 adjacent their forward ends and are adapted to be folded against the bars 28 as shown in dotted lines in Fig. 4 and to be positioned with the said bars within 5 in the beam slots 17 in their folded relations and with the front strip 31 lying flush with the facing strip 20 as well as the forward faces of the main legs 12. It will be noted that positioning pins 35 are similarly carried beneath the beams 17 and bars 28 which are adapted to be received within similar sockets 36 of the legs 24 and 33 when the legs are in their folded relations.

From this detailed description of the invention, it will be seen that the lateral supporting frames may be completely folded at opposite sides of the table 10 positioned entirely beneath the table top 11 while the leaves 13 may be folded in compact arrangement upon the said table top and thus providing a complete table when the device is folded. It should be noted that the beams 17 as well as the bars 28 are positioned closer together at one side of the table than the other for allowing those at one side to be positioned between those at the other side of the table when folded and that guide members 37 are provided for the said beams 17 beneath the table top 11 and the supporting base 38 upon which the said beam flanges 22 slide, the said base being secured parallel beneath the table top 11.

When the device is folded the front strip 31 may be pulled outwardly allowing the legs 33 to drop to their vertical supporting position while the frame 16 may be outwardly arranged by inserting outward movement to the facing strip 20, whereupon the legs 24 will resume their vertical positions. The leaves 13 may be then extended and positioned upon the supporting frames in the complete table formation at either or both sides of the table 10 and is illustrated

at one side thereof in Figs. 2 and 3 of the drawing.

While the form of the invention herein shown and described is what is believed to be the preferred embodiment thereof, it is nevertheless to be understood that minor changes may be made in the form, proportion and details of construction without departing from the spirit and scope of the invention as claimed.

What I claim as new is:—

A device of the class described comprising a table having slots spaced apart at different distances in the opposite depending sides thereof and having lower extensions, beams slidably mounted through the said slots and having stop flanges on their inner ends and being provided with longitudinal grooves upon their upper sides, legs forwardly hinged beneath the said beams and slidably positioned through the said slot extensions, a transverse facing strip secured to the forward ends of the said beams and having an upper cut-away portion, bars slidably positioned within the said grooves, a front strip secured to the forward ends of the said bars and seated within the said cut away portion of the facing strip when the device is in its folded position and with the said facing strip and front strip flatly engaging the forward side of the table, front legs hinged forwardly to the said bars and slidably arranged within the said grooves when in their folded positions and foldable leaves for the said beams and bars hingedly connected to the said table.

In testimony whereof I affix my signature 80 in presence of witnesses.

MICHAEL KRECKOWSKI.
